UNITED STATES PATENT OFFICE

CHARLES P. HEKLER AND PAUL HORACEK, OF PHILADELPHIA, PENNSYLVANIA

EAR PROTECTOR

Application filed May 19, 1932. Serial No. 612,299.

Our invention relates to ear protectors, that is to say, to shields adapted to be placed over the ears to protect the same, while various manipulations are performed upon the hair, such as shampooing, finger waving, drying, etc., whereby the ears will be protected from the entrance of water, soap, and the like, and from direct physical contact with the apparatus used in such manipulations.

The principal object, therefore, of our present invention is to provide a simple and efficient device which may be readily and expeditiously applied by operators in hair-dressing establishments and the like, for the purpose of protecting the ears of persons whose hair is being manipulated in the various ways above mentioned.

With the foregoing object in view, our invention contemplates the provision of a pair of protecting devices, suitably shaped so as to be readily placed over the ears, which will prevent the entrance of water, soap, and the like, into the ear canals; which will prevent the apparatus used by the operator from coming in contact with the ears of the wearer; and which will offer a minimum of obstruction to the various manipulations of the operator.

The nature and characteristic features of our invention will be more readily understood from the following description, taken in connection with the accompanying drawing forming part hereof, in which:

Fig. 1 is a perspective view of an ear protector embodying the main features of our present invention;

Fig. 2 is a front elevation of one of the ear covering members of the device;

Fig. 3 is a similar elevation of the other side thereof; and

Fig. 4 is a vertical section, taken approximately on the line 4-4 of Fig. 3.

Referring to the drawing, the device of our invention there shown comprises a pair of ear covering members 5, mounted at the respective ends of a U-shaped spring 6.

The ear covering members 5 are preferably made of suitable sheet material, such as aluminum, stainless steel, or a fireproof

cellulose composition, and each of said members comprises a main body portion 7, suitably shaped in dished form and of suitable size to cover the ear of the wearer.

Extending along the top and rear portions of the main body portion 7 of the device is an angular rim 8, which serves to provide a pocket 9 for the reception of the upper portion of the ear.

The marginal edge of the angular rim 8 blends into the lower part of one side edge and the bottom edge of the body portion 7, and around the edges of the opening thus defined there is provided a bead 10, upon which is mounted a split tubular gasket 11, preferably made of rubber or other suitable resilient material.

The gasket 11 is adapted to bear against the head of the wearer around the ear, and effectively serves to prevent the entrance into the ear canal of water or other liquids which may be used by the operator, and further serves as a means of electrical insulation to protect the wearer in the event of short circuits in the electrical apparatus sometimes used in various manipulations upon the hair. For the same purpose, the spring 6 may be covered with a suitable insulating envelope 12.

The preferred means of attaching the spring 6 to the ear covering members 5 consists in passing the same through a slot 13 near the bottom of the body portion 7, and then securing the same on the inside of said body portion 7 by means of a rivet 14.

To place the device upon the ears of the wearer, it is merely necessary to pull the ear covering members apart, then to slide the same upwardly until the upper portions of the ears are positioned within the pockets 9, and then to release the same to permit the spring to hold the ear covering members against the head of the wearer, the gasket 11 bearing against the surface of the skin surrounding the ears. When the device is in place, the spring 6 will be positioned under the lower jaw of the wearer.

We claim:

1. A protector for the ears comprising a pair of ear covering members made of sheet

100

- material, each comprising a dished body portion and shaped to form a pocket-like device having a constricted opening, and a gasket mounted at the edges of said opening; and a
6. **U**-shaped spring upon the ends of which the ear covering members are mounted.
2. A protector for the ears comprising a pair of ear covering members made of sheet material, each comprising a dished body portion and an inwardly extending rim along the top and one side thereof having its edges blending into the edges of the side and bottom of the body portion, and a gasket mounted upon said edges.
10. 3. A protector for the ears comprising a pair of ear covering members, each comprising a dished body portion and an inwardly extending rim along the top and one side thereof having its edges blending into the edges of the side and bottom of the body portion, said edges being provided with a bead, and a gasket comprising a split tubular member made of resilient material mounted upon said bead.
15. 20. 4. A protector for the ears comprising a pair of ear covering members, each comprising a dished body portion and an inwardly extending rim along the top and one side thereof having its edges blending into the edges of the side and bottom of the body portion, said edges being provided with a bead, and a gasket comprising a split tubular member made of resilient material mounted upon said bead; and a **U**-shaped spring upon
25. 30. 35. 40. 45. 50. the ends of which the ear covering members are mounted.
5. A protector for the ears comprising a pair of ear covering members, each comprising a dished body portion and an inwardly extending rim along the top and one side thereof having its edges blending into the edges of the side and bottom of the body portion, said edges being provided with a bead, and a gasket comprising a split tubular member made of resilient material mounted upon said bead; and a **U**-shaped spring upon the ends of which the ear covering members are mounted, said spring being covered with an insulating envelope.
55. 58. In testimony whereof, we have hereunto signed our names.

CHARLES P. HEKLER.
PAUL HORACEK.
